RADIO TUBE OR THE LIKE

Milton R. Schulte, West Orange, N. J., assignor to
 Tung-Sol Lamp Works Inc., Newark, N. J., a
 corporation of Delaware

Application July 20, 1939, Serial No. 385,470

3 Claims. (Cl. 250—27.5)

This invention relates to radio tubes and the like electric devices.

One object of the invention is a novel and improved radio tube.

A further object of the invention is a novel and improved radio tube which will be economical to manufacture and efficient in operation.

A feature of the invention is the elimination of the usual glass stem of the tube and the substitution therefor of a plain disk or button of glass with consequent saving in cost and economy in available space within the tube.

A further feature of the invention is the bringing of the lead wires through the seal between the disk and bulb at widely separated points to simplify the construction and to reduce the capacity effect between the leads, particularly that between the control grid lead and anode lead.

Other features of the invention will become apparent as the description proceeds.

For an understanding of the invention, reference may be had to the accompanying drawing, of which—

Fig. 1 is a perspective view illustrating one stage in the assembly of the mount and the glass envelope of a tube embodying the invention;

Fig. 2 is a sectional view along the line 2—2 of Fig. 1 but showing the glass envelope sealed to the base;

Fig. 3 is a perspective view of the mount of a tube illustrating another embodiment of the invention; and

Fig. 4 is a vertical sectional view along the line 4—4 of Fig. 3 but showing a completed tube.

In the embodiment of the invention illustrated in Figs. 1 and 2, a plain disk 2 of glass or the like forms the lower closure of the tube, the disk 2 being sealed to the tubular envelope 4 of glass or the like as shown in Fig. 2. All of the lead wires 6, 7, 8, 9 and 10 for the electrode assembly 12 are brought out through the seal between the disk and envelope at widely separated points; the leads 6 and 9 for the control grid and anode respectively being brought out at diametrically opposite points of the disk 2. The electrode assembly 12 may be supported in any suitable manner within the tube. In the particular tube illustrated, the electrode assembly 12 is of the type having vanes 14 which frictionally engage the inner walls of the envelope 4 and hence little, if any, additional support is required. Such additional support may be provided, as shown, by the grid lead 6 and anode lead 9.

In manufacturing the new tube, the lead-in conductors are first bent around the edge of the disk 2. The elements of the electrode assembly are then connected directly to the lead-in conductors; the conductors 7 and 10 preferably being first passed through an insulating block 16 of mica or the like. The cylindrical glass envelope 4, which has first been tubulated at its upper end and provided with an exhaust tube 18, is then slid over the assembly and its open lower end fused about the disk 2 and lead-in conductors. The tube is then heated, and evacuated or gas filled, as desired, in the usual manner and the exhaust tube sealed off.

The tube illustrated in Figs. 3 and 4 differs from that of Figs. 1 and 2 in that additional supporting means are provided for the electrode assembly. In this latter embodiment of the invention a disk 2' forming the base of the tube is provided with upstanding insulating members 20, which may be of glass and fused directly to the disk 2'. The members 20 are vertically slotted at their upper ends to receive the vanes 14 as shown. This makes a compact unitary arrangement of base and electrode assembly ready for sealing into the envelope 4. As with the tube of Figs. 1 and 2, the lead-in conductors are brought out at separated points through the seal between the disk 2' and envelope 4, with the leads 6 and 9 separated the maximum distance.

From the above description it will be apparent that the invention provides a tube in which the cost of manufacture is materially reduced as compared to that of the type of tube having the usual relatively expensive glass stem both because of the lesser cost of the simple disk of glass or the like forming the base of the tube, and because there will be less breakage during the sealing operation. Furthermore, the bringing out of the lead-in conductors through the seal at widely separated points reduces the capacity effects between the leads, particularly between the grid and anode leads, and hence improves the operation of the tube. The provision of the disk base also increases the usable space within the envelope, permitting either a larger electrode assembly or a smaller envelope as compared with tubes now on the market.

Although the invention has been described as embodied in an improved radio tube, obviously certain features thereof are applicable to other types of glass enclosed electrical devices, such as incandescent lamps, flash-lamps or the like.

The following is claimed:

1. A radio tube comprising in combination, a

disk of refractory material, an envelope of refractory material sealed to the periphery of said disk to form an enclosure therewith, an electrode assembly within the enclosure, lead-in conductors for the electrode assembly, said conductors passing through the seal between said disk and said envelope at separated points and upwardly projecting insulating members secured to said disk for supporting said assembly.

2. In a radio tube comprising an envelope, an electrode assembly including an anode and a control grid within the envelope, a closure for one

end of the envelope and lead-in conductors for the electrode assembly, the improvement comprising forming the closure of a disk sealed at its periphery to the envelope with the lead-in conductors passing through the seal and with the lead-in conductors for the anode and control grid diametrically disposed in the seal.

3. A radio tube according to claim 2 including upwardly projecting insulating members secured to said disk for supporting said assembly.

MILTON R. SCHULTE.
